UNITED STATES PATENT OFFICE.

ARTEMAS A. KENT, OF DENVER, COLORADO.

ORE-CONCENTRATOR.

SPECIFICATION forming part of Letters Patent No. 280,934, dated July 10, 1883.

Application filed December 11, 1882. (No model.)

To all whom it may concern:

Be it known that I, ARTEMAS A. KENT, of the city of Denver, in the county of Arapahoe and State of Colorado, have invented certain new and useful Improvements in Ore-Concentrators, of which the following is a specification.

In washing pulp containing ores of gold or silver, I employ a series of separate and distinct ore receivers or sluices closed on their sides, arranged transversely upon a suitable inclined support or way having a transverse oscillating motion, upon which they are adapted to be moved upward past the feeding-point, and in such movement to allow the surplus matter of water and gangue, by reason of the travel of said receivers up said inclined way, to pass down from one receiver to another placed upon or entering the inclined way in succession at the lower end of the series, leaving the particles of gold or silver to be carried up in the receivers and removed therefrom in any suitable manner at the upper end of the inclined way. The pulp is subjected by this means to a repeating operation in separate and distinct parcels of such quantity in each parcel as can be treated to the best advantage to separate and concentrate the metallic particles within the separate receivers as they travel upward on the incline under a downward flow of the water, each receiver delivering the settling at the upper end of their travel and the water at the point of commencing their upward travel. This construction allows the gangue matter and lighter pulp to be worked off continuously into separate and distinct communicating receivers moving at different levels, each retaining and carrying upward from the lowest to the highest or discharging point whatever of value may escape from the one above into the one below. The distinguishing feature of such operation is that the concentrated particles of ore are retained in the separate and distinct series of moving receivers or sluices and delivered at a point opposite to the direction of the flow of the washing and separating medium; nor is it material by what means the pulp receivers or sluices are moved up the inclined way in effecting this washing and concentrating operation.

The accompanying drawings represent my improved ore washer and concentrator, which

I will now proceed to describe, preparatory to a designation of what is claimed as my invention.

Figure 1 represents a view in perspective of the machine. Fig. 2 represents in elevation the upper or discharging end of the inclined way, showing the means by which the receiver, which is highest in the series, is held in proper relation as to pitch with the others below it until in its travel it is in position to discharge its contents. Fig. 3 represents one form of receiver with its sides closed and connected with a link of an endless revolving chain, to which the series may be secured, and by which they may be carried over the inclined way. Fig. 4 represents a vertical longitudinal section, showing the receivers adapted to be moved up the inclined way in separate non-connected relation instead of in joint-connected series, the operation being the same in both constructions and the results produced identical. Fig. 5 represents a vertical longitudinal section of the apparatus shown in Fig. 1, illustrating the position of reel E when it is depressed to its lowest point, its shaft being in the lowest part of the slots v, and its highest point of connection with the endless chain is against the fixed arm S, by which the depression of the reel is effected. Fig. 6 represents in cross-section three of the non-connected receivers operating on an incline, so as to carry out the repeating overflow process of concentrating the metal. Fig. 7 represents in perspective one of said non-connected receivers with inclined bottom and overflow lip at one side.

The receivers, of which two forms are shown, are so constructed with closed sides and arranged to travel upward upon an inclined support that the higher will discharge their surplus matter of water and gangue into the next one below throughout the series, retaining in each such metal particles as settle therein.

A tramway or support, B, of any suitable construction to form a rigidly-connected frame or carriage, is suspended by hangers b b in an inclined position longitudinally to a suitably-constructed main frame, A. The hangers b are pivoted to the upper cross-beams of said main frame and to the opposite sides of the inclined tramway, near its upper and its lower ends, as shown in Figs. 1, 4, and 5. This

tramway or support is formed with vertical sides m' , between which the ends of the receivers move up upon the inclines m , and these sides m' project only enough to form such guides. In Figs. 1 and 5 these receivers are shown as being closed on their sides and connected so as to have an endless traveling movement over reels or heads, while in Fig. 3, I have shown one of the receivers of the same construction as in Figs. 1 and 5, as being connected to a link of a chain composed of cross-joint rods J and hinges j , to which the receivers are separately secured, so as to be carried side by side upon and over the inclined support B , with the ends of the hinge-rods J or the ends of the connected receivers resting upon the ways m . It is not essential, however, that the receivers be connected to and operated as an endless chain, because they may be placed separately and continuously by hand upon the lower end of the inclined support and moved upward thereon by any suitable means, either continuously or at intervals, without affecting or modifying their operation in washing and concentrating the ore; nor does the form of the receiver make any material matter, so long as they are closed on their sides, arranged side by side, and made so that one communicates by an overflow with the one next below it in the series. Both forms of the receivers are shown in Figs. 1 and 5; and while I have described them as having closed sides, I prefer to make the bottom inclined, extending from the highest closed side and terminating on a level with the apron k at the overflow side, as shown in Figs. 5, 6, and 7. The inclined bottom may be of wire-gauze, as shown in Figs. 6 and 7; or it may be imperforate, as shown in Fig. 3, and in either case the deepest part of the receiver collects the metal particles. When used in the endless-chain form, said-chain is mounted upon suitable reels or heads, E E' , at its upper and lower ends, the shafts of which are journaled in some part of the inclined support. These reels or heads are adapted to conduct the ore-receivers around the ends of the inclined support, and are for this purpose notched in a manner to engage the rods J of the endless chain.

The ore-receivers form settling-troughs, closed at their sides, each being provided with a projecting lip or apron, k , arranged to overlap the upper side of the next adjoining receiver below, by which to conduct the surplus contents of one receiver into the next one below it in the inclined series. The receiver may be made with a flat bottom with the overflow lip or apron k , as in Fig. 3, or with an inclined bottom and an overflow lip or apron, as in Figs. 5, 6, and 7. When the receivers are operated in the endless-chain form provision is made for holding the receivers as they reach the upper or discharging point in the same relative position as to pitch as the others below it until the moment each receiver is brought to the point at which it is quickly turned into a vertical position to dis-

charge the contents, as in Figs. 2 and 5. But for this provision the receiver would commence to tilt before reaching the proper point, and would thereby occasion loss of the metal. This proper dumping of the receivers is effected as follows, viz: The journal-bearings at each end of the reel E' are slotted at v , and a guide, S , is rigidly attached to the inclined support B on each side above the reels. The reel-journals are supported upon springs c , which exert a lifting action upon the reels, which are thereby held up firmly against the under sides of the guides S , and may be depressed by reason of their journals passing through the slots v in the inclined support, as stated. A ratchet, P , (shown in Fig. 2,) is fastened upon the end of the reel E' , and a pawl, p , pivoted to a lever, R , is adapted to engage with said ratchet, the said lever being loosely fitted upon the end of the reel-journal outside of the ratchet. As the lever R is depressed by hand, the pawl p , engaging with the ratchet, turns the reel E' , which, being engaged with the endless chain of the receivers, moves them up the inclined support. Now, as the rigid guide S will not allow the upper side of the reel E' as it is turned to rise above the line of the inclined support B , the reel must therefore be forced downward sufficiently to allow it to follow under the guides S , and in this way hold the receiver in passing to a dumping position in the same position as to pitch that it had when resting upon the inclined support. In this action it will be seen that the receiver leaves the inclined support in passing upon the reel-heads at the dumping end of the inclined support. The object of this construction is therefore to hold the receiver in proper position while passing out and over the reel ends to discharge the contents which may have settled therein.

The sidewise oscillating movement of the inclined support is effected as follows, viz: A rock-shaft, F , is mounted in bearings in the cross-beams of the frame A , and is connected by a depending arm, f' , at each end, to the hangers b by a link-joint near their lower ends. A lever, f , is firmly secured to the rock-shaft F , and has its lower end connected by a pitman-rod, x , to a crank, y , of the shaft G , having the driving-pulley g . This construction gives the advantage of equalizing the transverse oscillating motion of the inclined support by reason of connecting the depending arm f to the rock-shaft F in the middle of its length, and connecting said rock-shaft by depending arms to the hangers b . This movement of the inclined support causes it to strike against bumpers a a , placed upon the standards of the frame A , and may be used at both sides of said frame, so as to assist in agitating the ore within the receivers.

In addition to the bumpers a a , spring-bumpers i i may be attached to the frame-standards, as shown in Fig. 1, to assist in giving the desired jar, and assist, by their spring action, the side motion. These spring-bump-

ers are short rods, mounted in brackets and provided with coil-springs, as shown, so as to yield when struck and force the inclined support to one side in unison with the movement of the crank.

The receivers may be used in non-connected relation—that is, they may be placed by hand upon the lower end of an inclined support and moved upward in succession by a push-lever, O, and thereby dislodge the uppermost one in succession, to be removed by hand. This construction is shown in Fig. 4, which is intended to illustrate how the disconnected receivers D may be moved up the inclined support, receive the pulp and water, and deliver the washed and concentrated metallic particles at the upper end of the incline support and at a point above that at which the water escapes. In this function the receivers are identical, whether connected or disconnected. In operating with the disconnected receivers in this way, I provide a spring-stop, N, to prevent the receivers from sliding down the incline; and it will be understood that the pulp is fed into the receivers, and as they are moved upward in series the uppermost one is dislodged, as at L, Fig. 4. The push-lever is pivoted to some fixed part of the frame at O', and the inclined support B is held against the action of the push-lever by means of rods O², pivoted to the frame A and to the under side of the inclined support, so that when the receiver is placed upon the ways m m' of said support against the lowest one of the series of receivers, the lever is pushed forward against the lowest receiver, and thereby pushes the series upward upon the inclined support, so that the spring-catch N catches against the lowest side of the end receiver, and thus holds the series in position to be intermittently moved upward. The spring-catch is shown in Fig. 4 as attached to the under side of the way m', and it will be understood that a similar spring-catch is secured to each way, so as to hold the receivers at both ends in proper relation. In this construction a side stroke is given to the receivers by the same means as that shown in Fig. 1.

The ore should be fed into the second or third receiver from the uppermost one by a suitable conduit or feeder placed at U in Fig. 5 below the point at which the water from the pipe W is supplied to the receivers by the branch pipe w. Branch pipes w' may be arranged to project one or more streams of water into the receiver as it is turned in the position to dump its contents, as shown in Figs. 1, 2, and 5. As the pulp is moved upward past the feeding-point the surplus water flows downward, carrying with it a portion of the pulp, so that each receiver of the moving series is filled with water, and as they move upward past the feeding-point they receive a fresh supply of water. This washes out the lighter and gangue parts of the pulp, leaving in each receiver whatever of the metallic substance may settle into the bottom to be carried

up and discharged with the water into a vessel, for subsequent treatment in a smelter. Each receiver is supplied with a certain amount of ore and treats it by itself, retaining the metallic particles which settle therein, leaving the surplus water to have a gentle flow from one into the other to carry off the earthy matters by a repeating process, and thereby produce a very effective washing, separating, and concentrating operation upon the pulp, saving whatever metal may be in it.

It is the inclined relation of the receivers that produces the repeating overflow for the surplus water, and it is the employment of receivers closed on its sides that effects the concentration of the metal under such repeating overflow.

I claim—

1. In a machine for washing and concentrating ore, the combination of a series of separate ore-pulp receivers or sluices having closed sides arranged side by side and suitable conduits for feeding the pulp and water thereto, with a suitable inclined way or support, means by which the receivers are moved upward past the feeding-point to collect by a repeating overflow from a higher into a lower one the metallic particles and deliver them at the highest point of said incline above and free of the washing-flow, substantially as described, for the purpose specified.

2. The combination of a series of separate ore-pulp receivers or sluices having closed sides arranged side by side and suitable conduits for feeding the pulp and water thereto, with a suitable inclined way or support for said receivers, and means, substantially such as described, for moving the said receivers upward upon an inclined support to deliver their contents above and free of the descending washing-flow, and suitable means for suspending and imparting a sidewise movement to the said inclined support, substantially as described.

3. In a machine for washing and concentrating ore, the combination of a series of separate receivers or sluices having closed sides arranged side by side and forming an endless carrier, means for imparting thereto a progressive upwardly-inclined motion, an inclined support, suitable means for feeding the ore-pulp and water to said receivers at a point below that at which the concentrated metallic particles are discharged, and suitable means for moving said receivers upward upon said inclined support, whereby the washing-overflow is in a downward direction over the series of receivers, and the metallic particles are carried upward in a contrary direction within the series of receivers, substantially as described.

4. The combination of a series of separate ore-pulp receivers or sluices having closed sides arranged side by side and forming an endless carrier, suitable reels or heads, and suitable means for imparting a progressive upwardly-inclined motion to the receivers, an inclined support, and suitable means for feeding the

ore-pulp and water to said receivers, with means, substantially such as described, whereby the receiver highest in the moving series is caused to maintain the same inclined position as those below it in passing over the reel to discharge the contents.

5. The combination, in a machine for washing and concentrating ore, the series of receivers or sluices having closed sides, forming an endless carrier, and suitable means for imparting a progressive upwardly-inclined motion thereto, an inclined support, suitable means for feeding the ore-pulp and water to said receivers, the slotted bearings *v*, the carrier reel-heads *E*, the guides *S*, having a fixed relation to said inclined support over said reel-heads, the springs *c*, arranged to exert an upward force upon the journals of said reel-heads, the ratchet *P*, pawl *p*, and the lever *R*, all constructed and adapted for operation substantially as described, for the purpose specified.

6. The combination, with the series of ore-

pulp receivers having closed sides, an upwardly-inclined supporting-way therefor, and suitable means for feeding the ore-pulp and water to said receivers, and means for moving them upward upon said incline, with the hangars *b b*, the rock-shaft *E*, its depending arms *f f' f'*, the crank-shaft *G*, the bumpers *a a*, and the springs *i i*, all constructed and arranged for operation substantially as described, for the purpose specified.

7. In a machine for washing and concentrating ore, the combination of a series of receivers closed on their sides, arranged side by side, each provided with an overflow-lip at its lowest side, extending over the highest side of the receiver next below, an inclined way, and means for imparting a progressive upwardly-inclined motion to said receivers, as shown, and for the purpose specified.
